UNITED STATES PATENT OFFICE.

MAX FIRST, OF BROOKLYN, NEW YORK.

FILLER-SLUG.

1,334,236.

Specification of Letters Patent. Patented Mar. 16, 1920.

Application filed November 20, 1919. Serial No. 339,496.

To all whom it may concern:

Be it known that I, MAX FIRST, a citizen of the United States, and a resident of the city of New York, borough of Brooklyn, in the county of Kings and State of New York, have invented a new and Improved Filler-Slug, of which the following is a full, clear, and exact description.

This invention relates to improvements in 10 filler slugs, and has particularly to do with cast metal filler pieces which may be cast in linotype or other similar machines, an object of the invention being to provide improved filler slugs of the character stated, which are 15 adapted to be assembled and provide a space in the type set up.

In ordinary printing it is frequently 20 necessary to leave a space for a cut or illustration and this space has ordinarily been provided by a solid assemblage of slugs which add considerably to the weight of the type and it is also an excessive use of metal. It is the purpose of my invention to cast a 25 slug which can be assembled to save metal and weight of the type set up.

With these and other objects in view the invention consists in certain novel features of construction, and combinations and arrangements of parts, as will be more fully 30 hereinafter described and pointed out in the claims.

In the accompanying drawings—

Figure 1 is a collective view illustrating the different parts of my improved mold; 35 Fig. 2 is a perspective view of one of the slugs cast in the mold;

Fig. 3 is a fragmentary sectional perspective view showing the mold in operative position;

Fig. 4 is a sectional perspective view showing the mold with the slug cast therein and the ejector in position for ejecting the slug;

Fig. 5 is a perspective view showing the manner of assembling the slug; and

Fig. 6 is a fragmentary perspective view illustrating in detail the manner of assembling two of the slugs.

1 and 2 represent the two longitudinal members of the mold and 3 and 4 are liners located in the molds, and it is, of course, to be understood that I may utilize any desired arrangement of liners to control the length of the slug cast.

5 represents a slug which is cast by my im-

proved mold and it will be noted that the 55 slug 5 is formed in one edge with a series of recesses 6 which are of slightly greater width than the thickness of the slug and extend to the center of the slug, so that two of these slugs can be assembled at right angles to 60 each other with their recessed portions 6 together, as shown in Figs. 5 and 6, and bring the edges of the slugs thus coupled in the same plane.

In use these slugs may be connected at 65 right angles to each other in any desired number and are preferably held at their edges by border slugs 7 and locked in the type to form a blank space for a cut or illustration or for any other purpose desired. 70

My improved mold is adapted to be secured to a mold disk 8 and I provide an ejector 9 of improved construction coöperating with the mold in the formation of the slug. To form the recesses 6 in the slug 5, the 75 member 2 of the mold is provided with integral angular enlargements 10 which press tightly against the face of the mold, and which, when the metal is forced into the mold, will form the recesses, as will be readily understood. The ejector 9 is made with a series of tongues 11 which are movable between the members of the mold and between the enlargements 10 to eject the mold after it is cast. 80

It is, of course, to be understood that I may provide the mold disk with the usual number of molds and may so arrange the parts as to cast the slugs of any desired length and thickness to suit the requirements 90 of the trade.

Various slight changes may be made in the general form and arrangements of parts described without departing from the invention, and hence I do not limit myself to the 95 precise details set forth but consider myself at liberty to make such changes and alterations as fairly fall within the spirit and scope of the appended claims.

I claim:

1. A filler piece, comprising a cast metal slug having throughout one edge a series of equally spaced recesses extending to the center of the slug.
2. A filler piece, comprising two series of 105 parallel cast metal slugs, the slugs of one series located at right angles to the slugs of the other series, and all of the slugs having

in their edges registering recesses extending to the center of the slugs, whereby the edges of all of the slugs are in the same plane.

3. A filler piece, comprising two series of parallel cast metal slugs, the slugs of one series located at right angles to the slugs of the other series, all of the slugs having in their

edges registering recesses extending to the center of the slugs, whereby the edges of all of the slugs are in the same plane, and border slugs at the ends of the first-mentioned slugs. ¹⁰

MAX FIRST.
